UNITED STATES PATENT OFFICE.

WILLIAM ROSENTHAL, OF NEW YORK, N. Y., ASSIGNOR TO ENID MANUFACTURING CO., INC., OF NEW YORK, N. Y., A CORPORATION OF NEW YORK.

BRASSIÈRE FOR FORMAL WEAR.

Application filed May 14, 1927. Serial No. 191,345.

This invention relates to brassières and more particularly to brassières for formal wear, an object of the invention being to provide a brassière which permits the wearing 5 of a very low back evening gown without exposing a portion of the brassière.

A further object is to provide a brassière which is crossed at the back and has garter attachments with shoulder straps supporting the brassière whereby the brassière is held in place and at the same time maintained smoothly around the body and functions as a support for the stockings of the 10 wearer.

15 A further object is to provide a brassière of this type which is extremely ornamental and attractive in appearance, which is comfortable to the wearer and which is especially designed to be worn with evening 20 dress.

With these and other objects in view, the invention consists in certain novel features of construction and combinations and arrangements of parts which will be more 25 fully hereinafter described and pointed out in the claims.

In the accompanying drawings—

Figure 1 is a three-quarter perspective view of a figure showing my improved brassière thereon;

Figure 2 is a back view of Figure 1;

Figure 3 is an exaggerated view in section on the line 3—3 of Figure 2.

1, 1 represent breast covering portions of 35 the brassière, which may be of silk or any other suitable material and which are connected by an elastic section 2. This elastic section may be covered with the same material used to make the breast covering portions, and the outer ends of the breast covering 40 portions have extensions 3 secured thereto which may be of the same material as the breast covering portions although of course I do not limit myself to the particular material employed.

Shoulder straps 4 are secured to the extensions 3 at the back of the brassière and at the upper edges of the breast covering portions 1. Elastic tapes 5 are secured to the 50 ends of the extensions 3 and have garters

6 at their extremities for attachment to the stockings 7.

The extensions 3, 3 are preferably widest at their points of attachment with the breast covering portions 1 and decrease in width to 55 their ends or at their points of attachment to the elastic tapes 5.

In use the shoulder straps are positioned on the figure and the extensions 3 crossed at the back, and at their point of crossing I 60 provide a coupling device 8 which may constitute an ordinary snap fastener although any other suitable coupling means might be employed. The garters 6 are attached to the stockings 7 and hold the brassière in a general V-shape at the back so that a dress having a very low back may be used without exposing the brassière.

It is this broad idea of a brassière crossed at the back and having hose supporters 70 thereon which constitutes my invention, and while I have illustrated and described a specific construction it is obvious that various slight changes and alterations might be made in the general form of the parts described without departing from my invention and hence I do not limit myself to the precise details set forth but consider myself at liberty to make such changes and alterations as fairly fall within the spirit and 75 scope of the appended claims.

I claim:

1. A brassière having its ends coupled at the back and having garter supporting elastic tapes at the ends of the brassière at the 85 back thereof, said brassière crossed at the back, and a coupling device securing the crossed brassière at the back.

2. A brassière having its ends coupled at the back and having garter supporting elastic tapes at the ends of the brassière at the 90 back thereof, said brassière crossed at the back, a coupling device securing the crossed brassière at the back, and shoulder straps connecting the front and back portions of 95 the brassière.

3. A brassière of the character described having breast covering portions, an elastic section connecting the breast covering portions, shoulder straps secured to the bras- 100

2
sière at the breast covering portions and adjacent the ends thereof, said brassière adapted to be crossed at the back, a coupling device connecting the crossed ends of the brassière, elastic tapes secured to the ends of the brassière, and hose attaching means at the ends of the tapes.

4. A brassière having its ends coupled at the back, garter supporting tapes at the ends of the brassière at the back thereof, 10 and shoulder straps connecting the front and back portions of the brassière.

WILLIAM ROSENTHAL.
